Gerardus Post Henrico INVENTOR.

BY

Gifford & Bell his ATTORNEYS

UNITED STATES PATENT OFFICE.

GERARDUS POST HERRICK, OF NEW YORK, N. Y.

TOOL FOR APPLYING AND TENSIONING WIRE ABOUT GLASS OR LENSES.

Application filed September 8, 1920. Serial No. 408,976.

To all whom it may concern:

Be it known that I, GERARDUS Post HERRICK, a citizen of the United States, residing at New York city, borough of Manhattan, in the county of New York and State of New York, have invented certain new and useful Improvements in Tools for Applying and Tensioning Wire About Glass or Lenses, of which the following is

10 a specification.

My invention relates to new and useful improvements in tools for applying and tensioning a retaining wire or strand about a glass or lens in order to secure the glass 15 or lens to a nose-piece of eye-glasses or other mounting. The invention particularly contemplates the provision of means for applying and tensioning a retaining wire upon an eye-glass or lens in the manner forming the subject matter of United States Letters Patent granted to me on September 23rd, 1919, No. 1,317,131, although it will be understood that the use or application of the appliance is not specifically limited for use in such relation.

20 The invention consists in the improvements to be more fully described hereinafter and the novelty of which will be particularly pointed out and distinctly claimed.

25 I have fully and clearly illustrated a form of my invention in the accompanying drawing to be taken as a part of this specification, and wherein:

30 Figure 1 is a view in side elevation, partly in section, of a preferred embodiment of my invention;

35 Figure 2 is an enlarged top plan view of certain portions of the appliance shown in Fig. 1;

40 Figure 3 is a top plan view of the complete device shown in Fig. 1.

45 Referring to the drawing by characters of reference, 1 designates a support for the eye-glass mounting or other device to which the lens or glass is adapted to be connected by a tensioning wire surrounding the lens or glass and connected to said mounting or device. This mounting support preferably consists of a substantial block of rigid material having an opening 2 to receive the cylindrical upper end 3 of a rigid post or standard 4, the lower end of which is adapted to be rigidly connected to a work bench by any suitable means (not shown), for example, a bench vice. Said mounting support 1 is adjustable upon said post in

order to take different positions thereon, for a purpose which is to be presently described. Any suitable means for accomplishing the adjustment for holding the 60 mounting support in place may be employed, but I prefer to employ a set screw 5 threaded through the rear of the element 1, the inner end of said screw being adapted to be seated in one or the other of two spaced seats or sockets 6, 7, in said post or standard 4. The mounting support 1 is provided with a recess or slot 8 extending longitudinally of the member 1 and preferably at right angles to the longitudinal 70 axis of the longitudinal element 4, said slot being adapted to receive a guard or nose-piece of the particular type of eye-glass mounting used, by way of example, in the drawing. The slot 8 divides the element 1 into an upper retaining plate 9 and a lower base portion 10, and in the side edges of said plate 9 are inwardly directed slots or recesses 11, 11^a, to receive a post of the eye-glass mounting, or other element to which the glass or lens is intended to be attached, said post being shown in elevation in Fig. 1 and in section in Figs. 2 and 3. The longitudinal axis of these slots 11, 11^a is preferably arranged obliquely of the longitudinal axis of the member 1, so that said slots extend inwardly and toward the opposite end of the said member from that bearing the set screw 5, for a purpose to be presently described.

55 12 designates a supporting member preferably in the form of a bracket, mounted preferably on the said post 4 and rigidly secured thereto by means of a set screw 13, or other clamping device, threaded through 80 the bracket and engaging at its inner end, with the said standard.

60 Mounted on the bracket is a swinging member 14 pivoted on a bolt 15, passing through an opening in the member 12, and retained by means of a nut 16 threaded on the lower end of said bolt. The pivot for the swinging member 14 is preferably arranged so that the longitudinal axis of said pivot is on a line extending through the forward edge of the slot 11 or 11^a, which at the time is being employed for supporting the post of the eye-glass or other mounting, and preferably as close as possible to the exit 100 of the hole in the post through which hole an end of the wire is drawn and bent laterally, or kinked in order to secure the glass

to the mounting and retain the tension in the wire, for example, in the arrangement shown and described in my said Letters Patent No. 1,317,131. On the bracket 14 5 is a support 17 for a wire tensioning device to be presently described. The support 17 is preferably in the form of a post having its lower end adjustably seated in an opening 18 in the bracket 14 to which it is held 10 by a set screw 19 let through the bracket and impinging the lower end of the member 17. The manner described of connecting the support 17 to the bracket provides for adjustment of the former relative to the latter. 15 In the upper end of the support 17 is a transverse opening 20 to receive a tubular member 21 constituting part of the wire-tensioning device, and having a longitudinal bore through which the wire being applied 20 to the lens or glass passes. The rear end of the member 21 is threaded, as at 22, to receive a threaded socket 23 on one end of an intermediate sleeve 24, in the rear end of which is slidably and rotatably arranged one 25 end 25 of a wire clamp 26 of any suitable construction. The wire shown at α passes through the bore of the member 21, through the sleeve 24, a bore in the shank 27 of the said wire clamp, and is held against slipping 30 by means of the jaws 28 of the wire clamp which exert their clamping action by means of a clamping screw 29 and wing nut 30 threaded thereon. The end of the member 26 which is slidably disposed within the 35 sleeve 24 is held within the sleeve by means of a shouldered cap 31 threaded onto the sleeve, as at 32, and having in its head an opening 33 through which the shank 27 slidably projects. The inner end of the 40 shank 27 is provided with a head 34 between which and the forward end of the sleeve 24, that is, the end toward the sleeve 22, is arranged an expansible compression spring 35 normally exerting its force to thrust the 45 clamp 28 lengthwise of the sleeve 24 away from said cap 31.

The operation of the appliance above described in applying a wire to a lens and lens mounting is as follows:

50 The wire α is attached to one end of the mounting or other device to be attached to the lens, and is carried around in the form of a loop, and then passed through the securing opening β through the lens mounting. 55 The mounting is then connected to mounting support element 1. Then the glass or lens having a peripheral groove is placed in the loop and the wire into said groove. The end of the wire passed through and emerging 60 from the securing opening in the mounting is passed through the member 22, the sleeve 24 and shank 27 and is secured to the clamp 28, as shown in Figure 1. The clamp 28 is then held by the hand of the operator 65 or otherwise against rotation and the sleeve

24 is rotated so as to back-off from the screw threaded sleeve 22, which operation serves to compress the spring 35 and place the wire about the lens under tension, so that the lens is strongly and rigidly gripped to its 70 mounting or other support. When the proper tension is obtained, the operator then swings the clamp and its support 17 on the pivot 15 in the direction of the positions shown in dotted lines and the arrows in Figs. 75 2 and 3 of the drawing for the purpose of kinking or bending the wire α at the point where it emerges from the securing opening β in the lens mounting whereby the tension in the wire about the lens is maintained and the lens is rigidly secured to the mounting. In the particular type of mounting shown in the drawing the side guards and the posts will be what are known as "rights" and "lefts," and I, therefore, provide the adjustable mounting support 1 with two slots 11 and 11^a so that one may be used when the lens is to be applied to the left-hand side of the mounting, and the other be used when the lens is to be applied to the right-hand side of the mounting, and the axial adjustment provides for the swinging of the mounting support 1 so as to bring either the right or left post of the lens mounting into proper alignment, as above 80 described, with the axis of the pivot 15 about which the element 14 swings. The adjustable feature of the element 17, afforded by the manner of connecting the same to the swinging element 14, provides for the proper 85 vertical and lateral adjustment of the member 22 of the wire clamp and tensioning device relative to the opening through the post of the lens mounting from which the wire emerges. 90

In Figs. 2 and 3 of the drawing the support for the lens mounting is shown swung to one of its points of adjustment to bring the post and the mounting in proper alignment with the axis of the pivot 15. It will 100 be understood that when the slot 11^a is used to support the post of the lens mounting that the element 1 will be swung so that the slot 11^a takes the position over the axis of the pivot 15. It will be understood that 105 the clamp may be swung on its joint in any direction to properly kink the wire at the point where it emerges from the opening in said post.

Having thus described my invention, 110 what I claim as new and desire to secure by Letters Patent of the United States is:

1. A tool for the purpose described, comprising a mounting-support, a tensioning-device, and a support for the tensioning-device permitting swinging movement thereof relative to the mounting support, said tensioning-device having means for gripping the wire to be placed under tension, and means permitting adjustment of the tension 115 120 125 130

while the wire is held by said device, said last mentioned means being independent of said swinging movement.

2. A tool for the purpose described comprising a mounting-support, and a tensioning-device having a swinging support on said mounting-support, said tensioning-device having means for gripping the wire to be placed under tension, and means permitting adjustment of the tension while the wire is held by said device, said last mentioned means being independent of said swinging movement.

3. A tool for the purpose described, comprising a standard, a mounting-support on the standard, a bracket on the standard, a tensioning-device, and a support for the tensioning-device mounted for swinging movement on said bracket, said tensioning-device having means for gripping the wire to be placed under tension, and means permitting adjustment of the tension while the wire is held by said device, said last mentioned means being independent of said swinging movement.

4. A tool for the purpose described, comprising a standard, a mounting-support on the standard, a second standard, a tensioning-device on the second standard, and a swinging support for said second standard whereby the latter may be swung relative to said mounting support.

5. A tool for the purpose described, comprising a standard, a mounting-support on the standard, a tensioning-device, a support for said device, and a pivot for said last named support arranged with its axis in line with said mounting-support, whereby the tensioning-device may be swung about a mounting held by the mounting-support, said tensioning-device having means for gripping the wire to be placed under tension, and means permitting adjustment of the tension while the wire is held by said device, said last mentioned means being independent of said swinging movement.

6. A tool for the purpose described, com-

prising a mounting-support, a tensioning-device, and a support for the tensioning-device permitting swinging movement thereof relative to the mounting-support, said tensioning-device having a clamp for gripping the wire to be placed under tension, and positive means for varying the position of said clamp relative to said mounting-support, whereby the tension may be increased by increasing the distance of the clamp from said mounting-support.

7. A tool for the purpose described, comprising a standard, a mounting-support on the standard, a second standard, a tensioning-device on the second standard, and a pivot between said standards permitting relative swinging movement between said mounting support and said tensioning device.

8. A tool for the purpose described, comprising, a standard, a mounting-support on the standard, a second standard, tensioning-means on said second standard, a pivot between said standards permitting relative swinging movement between said mounting-support and said tensioning-means, said mounting-support having a plurality of mounting holding means, and means whereby said mounting-support may be adjusted to bring one of said holding means in operative relation to the tensioning-means.

9. A tool for the purpose described, comprising a mounting-support having a slot adapted to receive a mounting part, tensioning-means, and a pivoted support for the tensioning-means, said pivoted support being in line with said slot.

10. A tool for the purpose described, comprising a standard, a mounting support adjustably mounted on the standard, and having a plurality of mounting receiving slots, a second standard, tensioning-means on said second standard, and a pivot between said standards permitting relative swinging movement between said mounting-support and said tensioning-means.

GERARDUS POST HERRICK.
